US0D1023932S

(12) **United States Design Patent** (10) **Patent No.:** **US D1,023,932 S**
(45) **Date of Patent:** **** Apr. 23, 2024**

(54) **CHARGING STAND FOR SKIN TREATMENT APPARATUS**

(71) Applicant: **LG ELECTRONICS INC.**, Seoul (KR)

(72) Inventors: **Dana Jung**, Seoul (KR); **Min-ji Seo**, Seoul (KR); **Gayeong Lee**, Seoul (KR)

(73) Assignee: **LG ELECTRONICS INC.**, Seoul (KR)

(**) Term: **15 Years**

(21) Appl. No.: **29/817,242**

(22) Filed: **Nov. 30, 2021**

(30) **Foreign Application Priority Data**

Jun. 17, 2021 (KR) 30-2021-0028890

(51) **LOC (14) Cl.** **13-02**

(52) **U.S. Cl.**

(57) **CLAIM**

The ornamental design for a charging stand for skin treatment apparatus, as shown and described.

DESCRIPTION

FIG. 1 is a front, left side perspective view of a charging stand for skin treatment apparatus showing our new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, left side perspective view showing the skin treatment apparatus in a mounted state; and,

FIG. 9 is a rear, left side perspective view showing the state in which the skin treatment apparatus is mounted.

The broken lines indicate portions of the article that form no part of the claimed design. The broken line showing of the skin treatment apparatus is provided for the purpose of illustrating environmental structure and forms no part of the claimed design.

1 Claim, 9 Drawing Sheets
